UNITED STATES PATENT OFFICE.

ROBERT R. KINTZ, OF MERIDEN, CONNECTICUT, ASSIGNOR TO INTERNATIONAL SILVER CO., OF MERIDEN, CONNECTICUT, A CORPORATION OF NEW JERSEY.

DESIGN FOR A PITCHER OR SIMILAR ARTICLE.

52,324.

Specification for Design.

Patented Aug. 27, 1918.

Application filed April 11, 1918. Serial No. 228,057. Term of patent 7 years.

To all whom it may concern:

Be it known that I, ROBERT R. KINTZ, a citizen of the United States, residing at Meriden, in the county of New Haven and State of Connecticut, have invented a new, original, and ornamental Design for a Pitcher or Similar Article, of which the following is a specification, reference being had to the accompanying drawing, forming part thereof.

Fig. 2 is a top view of the same.

I claim:

The ornamental design for a pitcher or similar article, as shown.

ROBERT R. KINTZ.

Witnesses:

CONSTANT K. DECHERD,
GEO. C. BREWER.
